ATT&S

UNITED STATES PATENT OFFICE

ISAAC C. FARBER, OF DETROIT, MICHIGAN, ASSIGNOR OF ONE-HALF TO STANLEY STAMPIL, OF DETROIT, MICHIGAN

ANTENNA

Application filed November 11, 1926. Serial No. 147,723.

My invention relates to an antenna adapted to be used in connection with radio apparatus and particularly to an antenna for radio receiving sets.

5 The invention has among its other objects the production of devices of the kind described which are convenient, compact, efficient and satisfactory for use wherever found applicable.

10 A particular object of the invention is to provide antennæ which will be particularly sensitive so that weak signals may be transmitted to the receiving set or to other apparatus.

15 Another particular object of the invention is to provide an antenna which can be easily erected in a relatively short period of time.

Still another particular object of the invention is to provide an antenna which will 20 transmit a minimum of static to the radio apparatus with which it is operatively connected.

Many other objects and advantages of the construction herein shown and described will 25 be obvious to those skilled in the art from the disclosure herein given.

To this end my invention consists in the novel construction, arrangement and combination of parts herein shown and described, 30 and more particularly pointed out in the claim.

In the drawings, wherein like reference characters indicate like or corresponding parts:

35 Fig. 1 is a simple vertical section taken through an antenna embodying the invention; and

Fig. 2 is a section taken on line 2—2 of Fig. 1.

40 In the drawings, wherein I have shown a preferred embodiment of the invention, the reference character 10 designates generally a metallic member or housing which preferably 45 comprises a metallic conical member 11 and a metallic conical member 12 held in spaced relation by an intermediate metallic member or spool 13, the members 11, 12 and 13 being preferably formed from sheet metal, although 50 it will be readily understood, as this descrip-

tion progresses, that they may be formed as castings if it is so desired.

In the illustrated embodiment of the invention, the spool 13 comprises a cylindrical wall 14 having angular flanges 15 and 16 formed integral therewith at its ends. The conical member 11 is preferably soldered or otherwise secured to the outer edge of the flange 15 as indicated at 17 and the conical member 12 is preferably similarly secured to the outer edge of the flange 16 as indicated at 18. 55

The housing 10 is preferably carried by a mast which is designated generally by the reference character 20 and preferably comprises a metallic rod 22 having a pointed end 60

23 upon which the conical member 11 is adapted to rest. Aligned with the metallic rod 22 and spaced therefrom is a metallic rod 25 which projects through the lower end of the conical member 12 and is rigidly secured 65

to the upper end of a rod 27, the metallic rod 25 being preferably insulated from the rod 27. In order to properly connect the adjacent ends of the rods 25 and 27, I provide 70 collars 30 and 31, the collar 31 being mounted 75

directly upon the upper end of the rod 27, while the collar 30 is threaded upon the lower end of a sleeve 32 which threads on to the lower end of the rod 25 with its upper end fitting snugly against and preferably soldered 80

to the lower portion of the conical member 12. Positioned between the collars 30 and 31 is a disc 33 of any suitable electrical insulation, said disc formed with a central upstanding portion 33' which extends into 85

the lower end of the sleeve 32 and against which the lower end of the rod 25 abuts. The collar 30 is preferably connected to the disc 33 by means of screws 35 while the collar 31 is secured to the disc 33 by screws 36. 90

From this connection it will be apparent that the opposed ends of the rods 25 and 27 may be quickly detached or secured together as desired. In the preferred embodiment of the invention, I preferably provide a member 95 or button 37 of electrical insulation between the adjacent ends of the rods 22 and 25, the rods being secured to each other and held in alignment by a spool 39 which is preferably formed of wood, but may be formed of any 100

other suitable electrical insulation. The spool 39 is preferably formed with heads 40 and 41 at its ends and a wire 43 is preferably strung between the heads, a plurality of tacks or equivalent devices 44 being employed to secure the wire to the heads. One end of the wire 43 is preferably soldered to the flange 15 as indicated at 46, and the other end of the wire is preferably soldered to the flange 16 as indicated at 47. As shown, the wire may lead from the soldered connection 46, over the head 40 and then longitudinally of the spool to the head 41 where it is secured to the head 41 by one of the tacks 44. The wire is then turned upwardly and strung along the spool to the upper head 40 where it is again secured to the spool by one of the tacks 44. The wire is strung back and forth longitudinally of the spool in this manner until it extends all around the spool. Obviously, when the wire is so arranged around the spool, the free end thereof will be positioned adjacent that point at which the wire was first secured to the spool. This free end is the one that is secured to the flange 16 in the illustrated embodiment of the invention.

Secured to the cylindrical wall 14 and intermediate its ends is a binding post 50 or the equivalent to which one end of an electrical conductor 51 is secured. In practice, the other end of the conductor 51 is secured to the antenna binding post of the receiving set or to the equivalent member of any other electrical device with which it is desirable to connect the improved antenna. Of course, it is readily understood that the binding post 50 need not be connected directly to the wall 14 of the spool 13, but may be connected to one of the flanges 15 or 16, or to one of the conical members 11 and 12, the spool 13 and the conical members 11 and 12 being electrically connected to each other.

In practice, I have found that the above described antenna is extremely sensitive when in operation and that it will collect and transmit weak signals to a radio receiving set so that the signals may be amplified there to give an audible signal in the telephones, the loud speaking unit or other device. One advantage of my improved construction is its compactness and the ease with which it may be erected upon any suitable support.

Having thus described my invention, it is obvious that various immaterial modifications may be made in the same without departing from the spirit of my invention; hence I do not wish to be understood as limiting myself to the exact form, construction, arrangement and combination of parts herein shown and described, or uses mentioned.

What I claim as new and desire to secure by Letters Patent is:

An antenna comprising a hollow spool shaped metallic conical ended member and a two piece rod, insulated from each other, dis-

posed longitudinally therein, the lower end of the lower rod extending exteriorly of said member and threadably engaging a sleeve, a flange threadably engageable with said sleeve, a second flange cooperating with the first said flange, but insulated therefrom, a supporting shaft, said shaft being engageable with and quickly detachable from said second flange, a wooden spool secured to said rod, in the center of said member, a plurality of pins disposed in the periphery of each head of the spool, a wire connecting said pins in the loops substantially parallel with the axis of the member, and the ends of said wire being soldered to said member and electrical means forming connection therewith.

In testimony whereof, I have hereunto signed my name.

ISAAC C. FARBER.
